UNITED STATES PATENT OFFICE.

JOHN E. CRIGGAL, OF NEWARK, NEW JERSEY.

WIRE-COILING MACHINE.

SPECIFICATION forming part of Letters Patent No. 609,011, dated August 16, 1898.

Application filed November 4, 1897. Serial No. 657,348. (No model.)

To all whom it may concern:

Be it known that I, JOHN E. CRIGGAL, a citizen of England, residing in Newark, in the county of Essex and State of New Jersey, 5 have invented certain new and useful Improvements in Wire-Coiling Machines, of which the following is a specification.

This invention relates to improvements in wire-coiling machines for forming coils or helices in strands of wire; and it has for its main object the provision of an improved mechanism of this class by means of which the leading-in wires of incandescent lamps may be formed at their outer ends into coils 15 or helices for receiving the ends of spiral conducting-wires carried by the socket or base of a lamp and forming a lamp-neck-receiving socket in substantially the manner shown and described in Patent No. 457,109, granted to 20 me August 4, 1891.

One of the main features of my present invention is the provision of a suitable rotary wire-coiling device or former coöperative with a suitable actuating device for rotating the 25 same, either one of these devices being capable of reciprocation for the purpose of rotating the coiling device or former.

In the preferred form of my invention the coiling device embodies a pair of rotary formers mounted on a slide carried by a suitable guide or guides for reciprocation between two extreme positions, these two formers being 30 so organized with respect to each other and to the actuating means therefor as to be capable of rotation in unison, so as to wind the two leading-in wires or other wires, as the case may be, to the same extent and form similar coils or helices, it being understood that both of the rotary formers should usually 35 be of the same diameter in order to form coils or helices of the same size. Preferably the rotary formers carried by the slides and which of course move therewith between the two limits of the range of movement of the slide 40 have suitable gears or pinions for rotating them, and these pinions may be driven in some suitable manner—as, for instance, by means of a rack or racks, which will usually be fixed on a proper support. This construction, however, may be varied within the scope 45 of this invention so long as coils in the wires

are formed substantially in the manner previously stated.

Although it will be apparent that formers may be employed which will permit the winding of a large number of coils of fine wire thereabout to form relatively long helices, yet ordinarily a few turns or coils will be sufficient for each wire if the wires being coiled are the leading-in wires of an incandescent 55 electric lamp. However, as some means should be provided for removing these coils readily from the formers when the coils or helices are completed, I prefer to employ coiling devices or formers movable longitudinally 60 in suitable bearings, in which they are mounted in such a manner that when the wires are being coiled these formers will project a sufficient distance from the bearings, and when the helices are completed the formers may be 65 withdrawn from the helices and into said bearings to permit the removal of the coiled wires. 70

Other features of my present invention relate to supporting means for holding the wires or the lamp in which they are embedded, as 75 the case may be, at a desired gaged distance from the formers, by means of which the coils or helices are to be formed in the wires, and also to cutting or shearing means for determining in advance the exact lengths of the 80 wires to be coiled, all of which will be described more fully hereinafter in detail.

In the drawings accompanying and forming part of this specification, Figure 1 is a plan of a wire-coiling machine embodying my 85 present invention. Fig. 2 is a sectional side elevation of the same, showing in dotted lines an incandescent lamp and its leading-in wires supported in position for the latter to be coiled by the machine. Fig. 3 is a vertical transverse section of the same, the section being taken in line 3-3, Fig. 2, and showing the formers projected into position to coil wires thereon. Fig. 4 is a similar view of a portion of the same, showing said formers retracted to permit the removal of the coils. Fig. 5 is a vertical transverse section of the machine, the section being taken in line 5-5, Fig. 2. Figs. 6, 7, and 8 are plans illustrating successive steps in the operations of determining the length of and coiling a pair of 90 leading-in wires of an incandescent electric 95 lamp. Fig. 9 is a plan of a wire-coiling machine embodying my invention, the machine being 100 similar to that shown in Fig. 1, but having a different form of actuating device.

lamp. Fig. 9 is a perspective view of a portion of the machine, showing the last step in the operation of coiling said wires.

Similar characters designate like parts in 5 all the figures of the drawings.

The several operative parts of my improved winding mechanism may be carried by any suitable framework—such, for instance, as a base B, of any kind and material. Upon this 10 base in the construction illustrated herein the several principal devices of the machine are mounted directly, these main devices being in this instance a wire-holding coiling device embodying one or more formers and an actuating device therefor, which may be in the 15 form of a rack, one of these devices being reciprocatory for rotating the coiling device, the third main member being a suitable wire holder or support—it being in this instance, 20 of course, a lamp-support—preferably adjustable toward and from the coiling devices, so as to form a gage for determining just how long the leading-in wires of the lamp should be prior to the operation of coiling them. In 25 addition to these main parts, which are mounted directly on the base B, there is another important device—viz., a shear or cutter mounted in this instance on a support or guide carrying a slide which may reciprocate the coiling device proper.

In the present construction I have shown and prefer to use a coiling device mounted on a slide—such, for example, as that shown at 2—for reciprocation between two extreme 30 positions, this slide being in the present instance carried by parallel guides, such as 3 and 3', and supported by the walls of parallel channels in the inner edges of the latter. These guides may be mounted on suitable supports 35 carried by the base B, said supports being indicated herein by 4. The coiling device proper embodies as its essential features one or more rotary formers, preferably two in 40 number, supported on the slide 2, so as to rotate in unison while reciprocating in unison with said slide. These two formers are designated herein by f and f', and they are supported in suitable bearings on the slide 2. Said 45 formers, which are supported, respectively, in the bearings 6 and 6', are not, however, formed each in one piece, but instead each is made up of two main members, one of which is in the nature of a sleeve and is supported for 50 rotation in its respective bearing 6 or 6' on the slide, but is held so that it will not move longitudinally, while the other main member is rotatable with, but is prevented from rotating relatively to, such sleeve and is movable longitudinally with respect to such 55 sleeve. The two members of the rotary former f are designated herein by 7 and 8, respectively, and the corresponding members of the former f' by 7' and 8', respectively.

The two members 7 and 7' constitute the 60 coiling devices or formers proper, and in this instance are supported in any suitable manner in the bores of the sleeves 8 and 8', rotary

movement of the coiling members 7 and 7' relatively to their respective sleeves 8 and 8' being prevented in any suitable manner, as 70 by means of pin-and-slot connections, such as that shown clearly in Figs. 2, 3, and 4.

For the purpose of enabling the two sleeves 8 and 8' to turn freely in the bearings 6 and 6' without moving longitudinally relatively 75 thereto the sleeves may be peripherally grooved, as shown in Figs. 3 and 4, and round-pointed screws, such as 9 and 9', may pass through the walls of the bearings and into said grooves. At the upper ends thereof the 80 sleeves 8 and 8' may have projecting stops, such as 10 and 10', which form means for engaging the ends of the wires at the beginning of the coiling operation, although, of course, the wires may be held in place in any other 85 suitable manner. For the purpose of operating the slide 2 I employ a suitable knob and spindle, (designated in a general way by K.)

As before stated, the two former devices are intended to be rotated in unison, and in 90 the present case the former-spindles 7 and 7' have secured thereto suitable gears or pinions by means of which the movements of a rack or other operating device may be imparted to the coiling devices. These gears on 95 the former-spindles may advantageously be in the form of long pinions, such as 12 and 12', in order that they may maintain their operative connection with the rack or other actuating device when they are moved from one 100 to the other of their extreme vertical positions.

For the purpose of connecting the two formers so that they will reciprocate in unison in the sleeves 8 and 8' I make use of the usual 105 connecting-plate, such as 13, which may be operated by a threaded rod, such as 14, screwed into the center of the plate and working in a longitudinal bore in a screw 15, connecting the slide and the actuating device or 110 rack. At its upper end the head of the rod 14 may be grooved peripherally to receive the recessed end 16' of a spring 16, by means of which in the construction illustrated the two former-spindles 7 and 7' will be held normally in their uppermost positions, as shown 115 in Fig. 3. Obviously the range of movement of the former-spindles in a vertical direction will be determined by the upper end of the screw 15 and the upper ends of the pinions 120 12 and 12'.

The actuating device by means of which the pinions 12 and 12' are rotated in this instance may be of any suitable type, but will 125 preferably be in the nature of a duplex rack, such as r, comprising two single racks, such as 17 and 17', the former of which is so positioned as to engage the pinion 12 and the latter the pinion 12'. Obviously when the slide 2 is reciprocated these racks will form 130 resistance-drivers for rotating the pinions in unison, but in opposite directions. In addition to forming an actuating device for the pinions 12 and 12' this duplex rack also has a

longitudinal slot therein, the inner end wall of which forms a stop for limiting the inward movement of the slide, while the outward movement of the latter may be determined by stops, such as those shown at 18.

For the purpose of reducing the two wires to be coiled to the proper length, especially when these are the leading-in wires of an incandescent lamp, I may make use of suitable 10 shearing or cutting means which may be mounted in any proper manner, preferably on the guides 3 and 3', said shearing means being designated herein in a general way by 15 s and comprising a fixed plate 19 and a swinging shear or cutting blade 20, operative in the usual manner.

In order to determine the position of the other end of the wire or wires when the latter is or are to be of a definite length, I may 20 make use of some suitable wire-support, such as that indicated herein by g, and which is clearly shown in Figs. 1 and 5. This support is preferably centrally slotted, as shown at 21, and may be secured in any desired 25 adjusted position, as by means of a clamping-screw 22. In the construction illustrated it constitutes an incandescent-lamp support and has a large opening therein adapted to receive the neck of the lamp, this opening 30 being designated by 23 and being preferably substantially in the form of a key-slot intersecting the upper edge of the support in order to provide a space for the entrance of the leading-in wires. This support constitutes a 35 gage and is co-operative with the shear to determine the length of the wire or wires to be coiled.

The operation of my improved winding-machine will be clearly understood by reference to Figs. 6 to 9, inclusive, in the former of which an incandescent-lamp bulb of any suitable type (designated herein by b) is illustrated and has sealed thereinto the usual leading-in wires w and w' which are to be coiled. It is to be noted that both of these wires are somewhat longer than is necessary and that when inserted between the two blades of the shear they will be reduced to the proper length, as will be apparent by referring to Fig. 6. In this view also the manner in which the wires are held between the stops 10 and 10' and the former-spindles 7 and 7' is shown clearly. As soon as the knob K is pushed in the slide 2 will move toward 50 the neck of the lamp-bulb, and the formers will be rotated, whereupon the two wires w and w' will be coiled around the projecting ends of the respective former-spindles 7 and 7', the coiling operation continuing until the slide 55 reaches the limit of its inward movement, as shown in Fig. 8, at which time each wire will have formed therein a series of coils or turns constituting a closely-wound helix. To remove the two helices from the former-spindles, the spring 16 should now be depressed, 60 whereupon the former-spindles will be re-

tracted within the sleeves 8 and 8', and hence will be withdrawn from said helices, whereupon the lamp may be moved from its support and the knob K drawn back to its original position. 70

It will be noticed, especially by referring to Fig. 9, that the upper ends of the sleeves 8 and 8' constitute stop-walls for supporting and locating the first coil of each helix, thus 75 assuring the proper and tight winding of the several superposed coils or turns.

It will be obvious that by means of my improved winding-machine the length of the wire or wires in which the coils are to be 80 formed may be gaged definitely and also the position of each coil or helix in the length of its wire, and this is a matter of very great importance in winding such coils in the leading-in wires of incandescent electric lamps, 85 for which use my improved winding-machine is especially designed.

Having described my invention, I claim—

1. In a wire-coiling machine, the combination, with a wire-holding coiling device embodying a bearing and a rotary former reciprocatory in said bearing longitudinally of its axis of rotation, of an actuating device for rotating said former, one of said devices being reciprocatory for effecting such rotation of 95 the former.

2. In a wire-coiling machine, the combination, with a wire-holding coiling device embodying a bearing, a rotary member, and a former rotatable in unison with the rotary 100 member and reciprocatory longitudinally of its axis of rotation, of an actuating device for rotating said former, one of said devices being reciprocatory for effecting such rotation of 105 the former.

3. In a wire-coiling machine, the combination, with a slide, of a pair of bearings on said slide; simultaneously-rotative formers mounted for reciprocation in said bearings; and a resistance-driver for rotating said formers on the reciprocation of the slide. 110

4. In a wire-coiling machine, the combination, with a wire-holding coiling device embodying a bearing, a rotary former reciprocatory in said bearing, and a spring for normally holding said former in position for coiling wire thereon, of an actuating device for rotating said former, one of said devices being reciprocatory for effecting such rotation of 115 the former. 120

5. In a wire-coiling machine, the combination, with a slide, of a pair of bearings on said slide; simultaneously-rotative formers mounted in said bearings and connected for reciprocation in unison; a spring for normally holding said formers in position for coiling wires thereon; and a resistance-driver for rotating said formers on the reciprocation of the slide. 125

6. In a wire-coiling machine, the combination, with a slide, of a rotary former mounted for rotation on said slide; a resistance-driver 130

for rotating said former on the reciprocation of the slide; and shearing means for determining the length of the wire to be coiled.

7. In a wire-coiling machine, the combination, with a slide, of a rotary former mounted for rotation on said slide; a resistance-driver for rotating said former on the reciprocation of the slide; shearing means; and a gage co-operative with said shearing means for determining the length of the wire to be coiled.

8. In a wire-coiling machine, the combination, with a slide, of a rotary former mounted

for rotation on said slide; a resistance-driver for rotating said former on the reciprocation of the slide; shearing means; and an adjustable gage co-operative with said shearing means for determining the length of the wire to be coiled. 15

JOHN E. CRIGGAL.
